MACHINE FOR COLORING MOTION-PICTURE FILMS.

Application filed April 8, 1924. Serial No. 705,121.

The present invention covers improvements in machines for coloring motion picture films, and is designed for handling such work where coloring matter is applied to a positive or finished film by bringing it into mobile pressurable contact with a similar film carrying coloring matter. The manner of preparing the films for this class of work, and particularly the preparation of the color or print plate, is well known in the art and need not be further enlarged upon in this case. It is further well known that the coloring matter is applied to the positive or finished film by absorption from print plate, and that the print plate carries this coloring matter upon certain portions of its gelatinous surface which correspond to the portions of the views upon the gelatinous surface of the positive film which it is desired to color. It may be here repeated, however, that irrespective of how carefully both the print plate and the positive film have been prepared, and ordinarily they are produced from the same negative, they shrink different amounts from being wet in the developing process, and also when being moistened in the transfer process, so that it is necessary to minutely adjust these films to bring them into perfect registration, and to maintain them in such registration during their continuous mobile contact.

Generally, the present invention includes new and novel means for adjusting the two films separately to bring them to registering dimensions, and to maintain them in such registration during their continuous movable contact; and the outstanding feature is an arrangement whereby the one film is bodily shifted, relative to the other, to bring them into registration. It also includes means for maintaining a longitudinal tension upon the films to insure an even and perfect pressurable contact between them. Details of construction and the mode of operation of the machine is given in the following specification; and in the accompanying drawings we have illustrated the preferred specific embodiment.

In these drawings:

Figure 1 is a front elevation of the machine;

Fig. 2 is a plan view thereof;

Fig. 3 is a sectional plan view taken as indicated by the line 3-3 of Fig. 1;

Fig. 4 is an end elevation taken as indicated by the line 4-4 of Fig. 1;

Fig. 5 is a transverse vertical section taken as indicated by the line 5-5 of Fig. 2;

Fig. 6 is a similar section taken as indicated by the line 6-6 of Fig. 2;

Fig. 7 is a fragmentary detail plan view of a tension roller;

Fig. 8 is an enlarged sectional view of one of the contact rollers; and

Fig. 9 is an enlarged fragmentary detail plan view of one of the contact rollers.

Attention is first directed to Figs. 1 and 2 wherein we have illustrated the general and relative arrangement of the several parts. In these views the numeral 10 designates an elongated rectangular base upon which the parts are supported. Standards 11, 12 and 13 are rigidly supported upon the base 10, preferably formed integral therewith; the standards 11 and 12 being situated adjacent its opposite ends with the standard 13 intermediate these two and preferably situated central thereof. A drum 14 is revolvably mounted upon a stub shaft 15, the latter supported in a suitable bearing 16 upon the upper end of the standard 13. This drum has peripheral teeth for engaging the perforations of the films and is mounted to rotate freely upon the shaft 15. It may be of any suitable size, but ordinarily it will be of comparatively large diameter, to reduce to a minimum the extent to which the films will be bent in passing thereover. Its peripheral teeth are of a width, in the direction of its axis, to closely engage the sides of the film perforations, so as to hold the films, when superposed thereon, in perfect lateral registration, but they will be somewhat shorter than the perforations, in the direction of its circumference, so the films may be relatively shifted thereon. The purpose of this construction will be more fully hereinafter explained.

The drum 14 is mounted a short distance above the base 10, and a pair of rollers 17, which we will hereinafter refer to as pressure rollers, are movably mounted upon the standard 13 to pressurably engage its periphery. These rollers are identical and are mounted to engage the periphery of the drum at points spaced substantially equidistant on either side of its vertical center, it being understood that the drum is mount-

ed to revolve in a plane extending longitudinally of and perpendicular to the base 10. These rollers are clearly illustrated in Fig. 8. They will preferably be constructed of 5 rubber, or a similar suitable material, having peripheral grooves 18 to permit the passage of the drum teeth when the two are in peripheral contact. These rollers have metal bearing sleeves 19 and are loosely mounted 10 to rotate upon shafts 20 carried upon the free ends of arms 21. The arms 21 are pivotally mounted upon pins 22, on the standard 13, so as to have an arcuate movement, as illustrated by the solid and dotted lines 15 in Fig. 1. Stop pins 23 are fixed in the standard 13 to limit the movement of the arms 21 in one direction, while the engagement of the rollers with the periphery of the drum 14 limit their movement in the 20 opposite direction. The rollers are yieldingly held in pressurable contact with the periphery of the drum by means of helical springs 24, secured at one end to the arms 21, intermediate their ends, and at their opposite ends to pins 25 on the standard 13. The springs 24 are mounted to either hold 25 the rollers 17 in peripheral engagement with the drum or to hold the arms 21 against the stop pins 23 when thrown in that direction. This is to permit the threading of the films onto or their removal from the drum.

Film feed sprockets 26 and 27, having peripheral teeth for engaging the perforations of the films, are rigidly mounted upon shafts 28 and 29, which, in turn, are revolvably journaled in suitable bearings 30 upon the upper ends of the standards 11 and 12. Similar guide sprockets 31 and 32 are situated immediately below the sprockets 26 and 27, but spaced slightly therefrom. These are mounted to rotate freely upon shafts 33 carried by the standards 11 and 12. Rubber contact rollers 34 and 35, similar to the rollers 17, are mounted to peripherally engage sprockets 31 and 32. The structure and operation of these parts are identical, so but one of them will be described. The roller 34 (see Fig. 9) is 35 mounted to rotate freely upon a shaft 36 carried by one end of an arm 37. The arm 37 is pivotally mounted, intermediate its ends, upon a pin 38 supported by the standard 11. A contractile helical spring 39 is secured at one end to the free end 40 of the arm 37 and at its opposite end to a pin 41, upon the standard 11, to yieldingly hold the roller 34 in peripheral contact with the sprocket 31, yet permit its separation therefrom to allow for threading the film therebetween.

It may be here noted that the sprockets 26 and 27 are providing for feeding one of the films through the machine, while the sprockets 31 and 32 function to properly

guide the film onto the sprockets 26 and 27, respectively and to hold it in substantial peripheral engagement therewith. Also the contact rollers 34 and 35 are provided to hold the film in substantial peripheral engagement with the sprockets 31 and 32, respectively. 70

A film tension roller 42 is carried by the standard 11, situated adjacent the sprockets 26, by means of which a suitable tension 75 may be exerted upon the film passing thereover, to hold it in close peripheral contact with the drum 14. The details of this roller are clearly illustrated in Figs. 1 and 7. It may be constructed of metal or a suitable soft material, such as rubber, and has a smooth peripheral surface to minimize liability of its injuring the gelatinous surface of the film. It is mounted to rotate freely upon a shaft 43 carried by the bifurcated end of an arm 44; this arm being pivotally mounted at its opposite bifurcated end upon a pin 45 extending through a lug 46 upon the standard 11. An adjusting screw 47 extends through a lug 48, formed or carried upon the standard 11, and engages the inner face of the arm 44, to adjustably raise the roller 42 against the tension of the film. Thus, after the film has 80 been adjusted over the sprockets 26 and 27, and under the drum 14, it may be brought to the proper tension merely by using the screw 47 to raise the roller 42 against it. 85 While it is contemplated that the films will be brought to proper registration in this device by shifting one relative to the other, as will later appear, in addition to exerting the necessary longitudinal tension upon the films to hold them taut during contact, slight inaccuracies of registration may be 90 cured by the use of the means just described. 95 A carriage, generally designated by the numeral 49, is mounted longitudinally slideable upon the base 10 (see Fig. 3). It has a base 50, with a finished bottom face which rides upon a finished top face of the base 10, to provide for accuracy of movement. It has a central longitudinal slot 51 into which a longitudinal rib 52, upon the base 10, 100 closely fits; and is held securely in place thereon by means of plates 53 removably secured to the rib 52 by means of screws 54; the plates 53 being of sufficient length to extend over the portions of the base 50 adjacent the rib 52. The slot 51 is somewhat 105 longer than the rib 52 to permit relative longitudinal movement of the base 50. 110

The base 50 is longitudinally moved and 115 adjusted by means of an adjusting screw 55 extending loosely through a lug 56, upon the base 10, and screw-threadedly engaging in an internally screw-threaded bore in a lug 57; the latter being carried by and preferably formed integral with the base 50. Collars 58 and 59 fixed upon the adjusting screw 120 125

55, hold it against longitudinal movement in the lug 56, and a knurled knob 60 is provided on its outer end by means of which it can be rotated by the fingers. Guide lugs 61 5 are also formed upon the base 10 to engage the longitudinal sides of the base 50 to further insure its accurate longitudinal movement.

Standards 62 and 63 are carried upon opposite ends of the base 50, preferably formed integral therewith, and are substantially in longitudinal alignment with the standards 11 and 12. Film feed sprockets 64 and 65 are fixed upon shafts 66 and 67, revolvably journaled in suitable bearings 68 upon the upper ends of standards 62 and 63. These sprockets 64 and 65 are substantially identical with the sprockets 26 and 27, and their function is likewise to feed one of the films through the machine in peripheral contact with the drum 14. Guide sprockets 69 and 70 and contact rollers 70 and 71 are mounted upon the standards 62 and 63, respectively. These are identical in structure and function with the sprockets 31 and 32 and rollers 34 and 35, therefore it is not necessary to explain them further in detail. Similarly a film tension roller 72 is supported upon the standard 62, which is identical in structure and function 30 with the roller 42, so no further explanation will be made of it. In fact, except for the rigid mounting of the standards 11 and 12 upon the base 10, and the mounting of the standards 62 and 63 upon the movable base 50, all the film handling mechanism carried thereby are substantially identical.

It may be well to here mention that the sprockets 26 and 27 and the sprockets 64 and 65 are mounted to rotate in the same plane 10 with the idler drum 14, as are also the contact, guide and tension rollers. This is necessary to hold the superposed films, as will be hereinafter explained, in alignment and against relative lateral movement.

The sprockets 26 and 27 are positively driven, in the directions indicated by the arrows in the several views, by means of a shaft 73—which may be operated by any suitable motive power—through the medium 50 of bevel gears 74 and 75 thereon, meshing with similar gears 76 and 77 keyed upon their respective shafts 28 and 29. The shaft 73 is revolvably journaled adjacent its ends in bearings 78 upon standards 11 and 12, and intermediate its ends in bearings 79 upon a standard 80, also fixed on the base 10.

The sprockets 64 and 65 are likewise positively driven, in the direction indicated by the arrows in the several figures, by means 60 of a shaft 81, through the medium of bevel gears 82 and 83, keyed thereon, meshing with gears 84 and 85 keyed upon the respective shafts 66 and 67. The shaft 81 is revolvably journaled adjacent either end in bearings 86 65 carried upon standards 62 and 63, upon the

base 50. The shaft 81 is driven through the medium of a spur gear 88 keyed thereon, meshing with a similar gear 89 keyed upon the shaft 73. To permit longitudinal movement of the carriage 49, during operation of 70 the machine, either one of the gears 88 and 89 is made somewhat longer than is ordinarily the case; and in the present instance I have shown this to be the gear 88. It is of sufficient length to permit any longitudinal 75 movement of the carriage necessary to correct inaccuracies of registration between the films. This, however, even under most unusual conditions will ordinarily be very slight.

In the operation of the machine it is first to be assumed that a print plate or film has been provided which carries coloring matter upon those portions of its gelatinous surface which correspond to similar portions of the views upon the positive or finished film which it is desired to color. As hereinbefore stated, even under the most favorable circumstances it is practically impossible to produce two such films which will register 85 perfectly when brought into facial contact, without the aid of some means for bringing them into such registration and maintaining them so during subsequent superposed movement.

It is not important in the present machine which of the films is supported in contact with the periphery of the drum 14 and which is the film superposed thereon; however, I will assume that the film, designated by the letter A is the print plate and the film designated by the letter B is the positive or finished film it is desired to color. The film A is first threaded through the machine by bringing it around the sprocket 31, swinging the contact roller 34 away from peripheral engagement therewith for this purpose, over the feed sprocket 26 and tension roller 42, under the drum 14, over the feed sprocket 27, around the guide sprocket 33 and between it and the contact roller 35. When this is done the film is properly adjusted so that the teeth of these several sprockets will properly engage its perforations; and it is drawn as taut as practicable 110 under the circumstances. If there is a slight looseness or lack of tension in the film after it is thus rove around the several sprockets, proper adjustment may be made with the tension roller 42, by means of its adjusting screw 47, to take up the slack or to exert the desired longitudinal tension. The film B is then similarly rove around the sprocket 68 and between it and the contact roller 70, around over the top of the sprocket 64, under 115 the drum 14, in facial contact with the film A, over the sprocket 65, around the guide sprocket 69 and between it and its contact roller 71.

In bringing the films A and B into the machine they are, of course, drawn 120 under the sprocket 64, around the contact roller 70, around over the top of the sprocket 65, under the drum 14, in facial contact with the film A, over the sprocket 68, around the guide sprocket 69 and between it and its contact roller 71. In bringing the films A and B 125 into the machine they are, of course, drawn 130

from suitable individual reels (not shown), and after they leave the machine they are ordinarily wound upon individual reels for drying, as moisture is commonly used in this process.

As in the case of the film A, the tension of the film B may be properly regulated by means of the tension roller 72 and its adjusting screw 47.

When the films A and B are threaded around the drum 14, the pressure rollers 17 are thrown to the positions indicated by the dotted line in Fig. 1, after which they are thrown to the positions indicated by the solid lines, where they are in pressurable peripheral contact with the films superposed on the drum. In addition to a pressurable facial contact being effected between the films A and B upon the drum, by adjustment of the tension rollers 42 and 72, the rollers 17 tend to further perfect this contact. Also, as the films A and B move through the machine in the direction indicated by the arrows in Fig. 1, and as a liquid is commonly used to moisten the gelatinous surface of either one or both before coming in contact upon the drum 14, the first roller 17 will serve to squeeze out excessive moisture from between the films and to substantially seal them together; this seal, however, is not sufficient to injure their facial surfaces when they are separated upon leaving the drum.

As the contact between the films upon the drum 14 is over a comparatively small arc of its circumference, the mechanism will be operated comparatively slow to give sufficient time for the absorption of the coloring matter by the film B from the film A. This period of contact may be regulated by varying the speed of operation of the several movable parts.

After the films have been threaded through the machine, as hereinbefore described, it is set in motion and the films continuously fed therethrough, through the medium of the shaft 73 driving sprockets 26 and 27 and sprockets 64 and 65 through the several gear trains as hereinbefore described. As the sprockets 26 and 27 and 64 and 65 are all geared to operate at the same peripheral speed they will all be of the same circumference and all driven by gears of a one to one ratio. The drum 14 not being driven, but merely idling upon its shaft 15 will be rotated by its peripheral teeth engaging in the perforations of the films A and B as they pass thereover.

In case the color carrying areas of the film A do not register with the corresponding portions of the film B, which it is desired to color, the film B may be bodily longitudinally shifted relative to the film A, through the medium of the adjusting screw 55 which moves the carriage 50 relative to

the mechanism carrying the film A and also relative to the drum 14. The extent to which the film B will have to be shifted, to bring it into registration with the film A, in any case, will be very slight and this may be very easily accomplished without stopping movement of either of the films A and B through the machine. The carriage 50 may be moved in either direction to correct inaccuracies of registration, while the peripheral teeth of the drum will hold the films in lateral registration.

While we have herein shown and described the preferred specific embodiment of my invention, we nevertheless reserve the right to make such changes and modifications in structure as will come within the scope of the appended claims.

Having described our invention, we claim,

1. In a machine of the class described, the combination of a revoluble drum, means to independently support two films in movable superposed relation on the periphery of said drum, said film holding means being positively driven to effect simultaneous movement of said films and arranged to hold the films in pressurable contact on the drum, and means in connection with said film holding means to longitudinally shift one of said films bodily, relative to the other, during movement, to effect their registration.

2. In a machine of the class described, the combination of a revoluble drum, means to independently support two films in movable superposed relation on the periphery of said drum, said film holding means being positively driven to effect simultaneous movement of said films and provided with means to hold the films in pressurable contact on the drum during continuous movement, means in connection with said film holding means to longitudinally shift one of said films bodily, relative to the other, during movement, and means to adjustably exert a longitudinal tension on either of said films, during movement, to effect their registration.

3. In a machine of the class described, the combination of a revoluble drum, means to independently support two films in movable superposed relation on the periphery of said drum, means to hold said films against relative lateral movement on the drum, said film holding means being positively driven to effect simultaneous movement of said films and provided with means to hold the films in pressurable contact on the drum during continuous movement, means in connection with said film holding means to longitudinally shift one of said films bodily, relative to the other, during movement, and means to adjustably exert a longitudinal tension on either of said films, during movement, to effect their registration.

4. In a machine of the class described, the combination of a revoluble drum mounted to rotate freely, means to support two films in movable superposed relation on the periphery of said drum, the drum having peripheral teeth to engage in the perforations of the films, said teeth being formed to prevent lateral shifting of the films thereon but to permit longitudinal shifting, and means in connection with the film holding means to longitudinally shift one of said films bodily, relative to the other, during their movement, to effect their registration.
- 15 5. In a machine of the class described, the combination of a revoluble drum mounted to rotate freely, means to support two films in movable superposed relation on the periphery of said drum, the drum having 60 peripheral teeth to engage in the perforations of the films, said teeth being formed to engage the film perforations closely in the direction of the axis of the drum, to prevent lateral shifting thereon, but to engage in said perforations loosely, in the direction of the circumference of the drum, to permit the films being longitudinally shifted thereon, means in connection with the film holding means to longitudinally shift one of said films bodily, relative to the other, during movement, and means 65 to adjustably exert a longitudinal tension on either of said films independently, during movement, to effect their registration.
- 20 7. In a machine of the class described, the combination of a film supporting member over which two films may be passed in pressurable contact, separate means to support each of two films in superposed relation on said member, one of said film supporting means being bodily shiftable longitudinally of its film for registering the two films, and means in association with the supporting means for independently and adjustably stretching either film to bring the two films to registering lengths. 70
- 25 8. In a machine of the class described, the combination of a film supporting member over which two films may be passed in pressurable contact, separate means to support each of two films in superposed relation on said member, means in association with the supporting means for independently and adjustably stretching either film to bring the two films to registering lengths, and means in association with one of said 75 supporting means for shifting the film carried thereby in a direction longitudinally of the film to place the two films in registering position.
- 30 In witness that we claim the foregoing 80 we have hereunto subscribed our names this 21st day of March, 1924.
